APPARATUS FOR REMOVING SHALE, COAL,
AND LIKE FROM GRAVEL

Chester I. Leveke, Des Moines, Iowa

Application May 12, 1941, Serial No. 393,048

8 Claims. (Cl. 209—464)

The principal object of my invention is to provide an efficient machine that will deliver washed gravel substantially free from coal, shale and other undesirable matter.

A further object of my invention is to provide an apparatus for removing shale, coal, dirt and the like from gravel that is easily operated and kept in repair.

A still further object of my invention is to provide a gravel cleaner that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Figure 1 is a side sectional view of my device.

Fig. 2 is a top plan sectional view of the lower portion of the trough portion of the device.

Fig. 3 is a top plan view of the rear portion of the device.

Fig. 4 is a cross sectional view of the apparatus taken on line 4—4 of Fig. 1 and more fully illustrates its construction.

Fig. 5 is an enlarged longitudinal sectional view of the bearing portion of the device.

In most uses for gravel it is necessary that the same be free from undesirable matter such as dirt, clay, shale, coal and like. To remove such undesirable substances I have provided a device that not only successfully accomplishes the desired results but delivers the gravel continuously and in a clean washed condition.

Referring to the drawings, I have used the numeral 10 to designate the trough portion of my device. This trough portion is designed to have its forward end elevated so that it extends forwardly and upwardly as shown in Fig. 1. The numeral 11 designates a vertical flange in the bottom of the trough portion and near its forward end as shown in Fig. 2. The numeral 12 designates the gravel outlet port between the flange 11 and the forward end of the trough member and located in the bottom of the trough member. The numeral 13 designates a bearing member secured on the rear end of the trough portion and communicating with the inside of the trough portion as shown in Fig. 5. The numeral 14 designates a stub shaft in the bearing 13 and extending forwardly a distance within the trough portion. This member 14 is se-

cured against movement relative to the member 13 by any suitable means such as a cap screw 15. The numeral 16 designates a passageway that extends longitudinally through the center of the stub shaft 14. The numeral 17 designates outwardly and rearwardly extending passageways in the member 14 communicating with the passageway 16 and the outer surface of the member 14 as shown in Fig. 5. The numeral 18 designates a floating sleeve embracing the forward end portion of the shaft 14, embracing the outlet ends of the passageway 17 and positioned within the trough as shown in Fig. 5. The numeral 19 designates a slot opening in the wall of the sleeve 18. The numeral 20 designates an elongated cylindrical element having its rear end embracing the sleeve 18 and with its wall relatively thick at one side relative to its diametrically opposite wall as shown in Fig. 4 in order that the same will be mounted eccentrically on and around the fixed stub shaft 14. This cylindrical member 20 extends forwardly within the trough 10 and has a plurality of radially extending propeller or agitating blades 21. These blades are mounted at an angle as shown in Fig. 1 so that when the cylinder 20 is rotated to the left it will move any material that the members 21 engage upwardly and forwardly. The numeral 22 designates a second elongated cylinder of a diameter less than the diameter of the cylinder 20 secured by any suitable means in its rear end portion to the forward end portion of the cylinder 20 and extending forwardly in the trough 10. This cylinder 22 also has the radially extending blades or propellers 23. The numeral 24 designates an elongated rectangular shaft square in cross section and cutting a path when rotated less than that of the path of the cylinder 22 and secured at its rear end portion to the forward end portion of the cylinder 22 by any suitable means. This shaft 24 extends forwardly in the trough member, has the usual blades or propellers 25 and has its forward end portion operating in the bearing member 26 and operatively secured to the large bevel gear 27 on the outer forward end of the trough as shown in Fig. 1. The numeral 28 designates a shaft designed to be operatively secured to any suitable source of rotary power. The numeral 29 designates a bevel gear on the shaft 28 and in engagement with the bevel gear 27. All of the cylinders 20 and 22 and shaft 24 are eccentrically mounted relative to the bearing members 13 and 26 in order that the cylinders and their propeller blades when rotated will

cut elliptical circles relative to the longitudinal axis of the stub shaft 14. All of the agitating or propeller blades are mounted at an angle so that when the cylinders 20 and 22 and shaft 24 are rotated to the left, material will be lifted upwardly and forced forwardly toward the discharge opening 12. If desired, the cylinders 20 and 22 and shaft 24 may be slidably and detachably secured together. The numeral 30 designates a pin or lug extending into the rear portion of the cylinder 20 secured thereto and loosely riding in the slot 19. This slot 19 in the member 18 extends through its forward end as shown in Fig. 5 in order that the cylinder 20 may be drawn forwardly from the sleeve 18. When the cylinders and shaft 24 are being rotated by the driving shaft 29, a certain amount of gravel, grit or like may get into the bearings. To eliminate the possibility of great harm being done to the bearings by such foreign matter, I have provided a water pipe 31 which has one end in communication with a suitable source of water under pressure and its other end communicating with the water passageway 16 as shown in Fig. 5. The numeral 32 designates a header in the cylinder 20 closing its rear end portion into a compartment 33 as shown in Fig. 5. Water from the pipe 31 will pass into and through the passageways 16 and 17, thereby washing the bearing assembly and keeping it substantially clear of undesirable foreign matter. The numeral 34 designates a perforated plate in the housing and closing the right hand lower corner portion of the trough as shown in Fig. 4. This plate extends from the rear end of the trough to the flange 11 as shown in Fig. 2 and its hole passageways 35 extend upwardly and inwardly toward the rotatable unit. The numeral 36 designates a water pipe connection communicating with the inside of the trough and below the plate 34 as shown in Fig. 4. This connection 36 is designed to be in communication with a source of water under pressure. The numeral 37 designates a similar plate having outlet passageways 38. This plate 37 encloses the left hand lower side corner of the trough and extends a substantial distance forwardly in the trough as shown in Fig. 1 at which point its forward end is closed. The numeral 39 designates a pipe unit on the rear end of the device communicating with the under side of the plate 34 and the under side of the plate 37. By this arrangement, when water is forced into the device through the connection 36, it will spray upwardly and inwardly through the water holes 35 and 38 and toward the rotatable agitating unit. The numeral 40 designates a water pipe extending upwardly from the forward end of the plate 34 and having its discharge end terminating into the trough and above the member 24. This pipe 24 injects water downwardly onto the mass of gravel as it approaches the outlet 12. The numeral 41 designates a plate on the rear top portion of the trough 10 and has the side walls 42 and 43 as shown in Fig. 3. The numeral 44 designates an elongated longitudinal slot opening in the center of the plate 41 for the escape of water, dirt, clay, shale, coal and like. The numeral 45 designates a hopper having its rear side wall removed and communicating with the top inside of the trough 10. This hopper is located near the rear end of the device and discharges above and to the right of the cylinder unit 20. The numeral 46 designates a baffle plate extending downwardly and rearwardly in

the forward end of the hopper 45. This plate 46 guides the material to be washed and cleaned downwardly and through the hopper and at the same time permits the light materials to be discarded such as shale, coal and like to bubble upwardly with the water, not be interfered with the downward flow of the material to be cleaned, and then out over the rear top portion of the device. The water line in the device should be maintained so that the lower marginal edge of this member 46 is adjacent the water line. This water line will decrease in depth due to the inclination of the device as it approaches the outlet opening 12. Guide plates 47 and 48 are placed in the upper right hand and left hand corner portions of the rear end portion of the trough to confine the material to be acted upon by the blades of the cylinder 20 and also to guide the undesirable light material upwardly toward and through the escape slot opening 44. By the rotatable unit being eccentrically mounted, greater agitation will be given to the material to be treated and clay, coal, shale or like undesirable material clinging to the gravel will be broken up and detached from the gravel as it is moved forwardly by the rotating unit. The paddles or blades 21, 23 and 25 not only break up and agitate the mass, but mix it and move it forwardly until it eventually passes through the opening 12 in a clean washed state.

Some changes may be made in the construction and arrangement of my improved apparatus for removing shale, coal and like from gravel without departing from the real spirit and purpose of my invention, and it is my intention to cover by my claims any modified forms of structure or use of mechanical equivalents which may be reasonably included within their scope.

I claim:

1. In an apparatus for removing shale, coal and the like from gravel, an elongated trough member extending forwardly and upwardly, an eccentrically rotatably mounted longitudinal element in said elongated trough member, projections on said element, a water supply means associated with said trough member, and a drive shaft operatively connected to said eccentrically rotatably mounted element for rotating the same.

2. In an apparatus for washing and cleaning gravel, an elongated trough member extending forwardly and upwardly, a cylinder inside the rear portion of said trough member having its rear end rotatably mounted on the rear end of said trough member, a second cylinder having a diameter less than the diameter of said first mentioned cylinder inside said trough member and having its rear end secured to the forward end of said first cylinder, a means for operatively rotatably mounting the forward end portion of said second cylinder to the forward end portion of said trough, propeller blades on both of said mentioned cylinders; said cylinders designed to be rotated within said trough member, a water supply element communicating with the inside of said trough member, and a plate on the upper rear end portion of said trough member having an opening.

3. In an apparatus for washing and cleaning gravel, an elongated trough member extending forwardly and upwardly, a cylinder inside the rear portion of said trough member having its rear end rotatably mounted on the rear end of said trough member, a second cylinder having a diameter less than the diameter of said first mentioned cylinder inside said trough member

and having its rear end secured to the forward end of said first cylinder, a means for operatively rotatably mounting the forward end portion of said second cylinder to the forward end portion of said trough, propeller blades on both of said mentioned cylinders; said cylinders designed to be rotated within said trough member, a water supply element communicating with the inside of said trough member, a plate on the upper rear end portion of said trough member having an opening, and vertically extending side walls on said plate extending parallel with said trough member.

4. In an apparatus for washing and cleaning gravel, an elongated trough member extending forwardly and upwardly and having a bottom side corner, a rotatably mounted unit inside said trough member, radially extending projections on said unit, a perforated plate within said trough member and closing the bottom side corner of said trough member, a water supply connection communicating with the under side of said plate, and a trough on the upper rear end of said first mentioned trough member having its forward and rear ends open.

5. In an apparatus for washing and cleaning gravel, an elongated trough member extending forwardly and upwardly and having a bottom side corner, a rotatably mounted unit inside said trough member, radially extending projections on said unit, a perforated plate within said trough member and closing the bottom side corner of said trough member, a water supply connection communicating with the under side of said plate, a trough on the upper rear end of said first mentioned trough member having its forward and rear ends open, a hopper communicating with said first mentioned trough member, extending through said second mentioned trough and having its rear wall removed, and a baffle member in said hopper extending downwardly and rearwardly.

6. In an apparatus for washing and cleaning gravel, an elongated trough member extending forwardly and upwardly and having a bottom side corner, a rotatably mounted unit inside said trough member, radially extending projections on said unit, a perforated plate within said

trough member and closing the bottom side corner of said trough member, a water supply connection communicating with the under side of said plate, a trough on the upper rear end of said first mentioned trough member having its forward and rear ends open, and an elongated slot opening in the bottom of said second trough.

7. In an apparatus for washing and cleaning gravel, an elongated trough member extending forwardly and upwardly and having a bottom side corner, a rotatably mounted unit inside said trough member, radially extending projections on said unit, a perforated plate within said trough member and closing the bottom side corner of said trough member, a water supply connection communicating with the under side of said plate, a trough on the upper rear end of said first mentioned trough member having its forward and rear ends open, an outlet opening in the forward bottom of said first trough member, and a flange in the bottom of said first mentioned trough member and to the rear of said outlet opening.

8. In an apparatus for washing and cleaning gravel, an elongated trough member extending forwardly and upwardly and having two bottom side corners, an elongated propelling and agitating unit rotatably mounted within said trough member, a plate closing one side corner bottom of said trough member to form a water conduit, a plate closing the other side bottom corner of said trough member, to form a water conduit, water passageways extending through said two plates and terminating in a direction toward said rotatably mounted propelling and agitating unit, a conduit having one end communicating with the space below one of said plates and its other end communicating with the space below said other plate, a water connection communicating with the under side of one of said plates, a plate on the rear top of said trough member having an opening and covering the rear top of said trough, and a baffle plate in the upper portion of said trough member extending from the side of said trough member to the under central portion of said last mentioned plate and adjacent said opening therein.

CHESTER I. LEVEKE.
